UNITED STATES PATENT OFFICE.

CLARENCE D. OVERSMITH, OF BUFFALO, NEW YORK.

DESIGN FOR AN ADVERTISING DISPLAY CASE.

60,465.

Specification for Design.

Patented Feb. 21, 1922.

Application filed March 11, 1921. Serial No. 451,587. Term of patent 3½ years.

To all whom it may concern:

Be it known that I, CLARENCE D. OVERSMITH, a citizen of the United States, residing at Buffalo, in the county of Erie and State of New York, have invented a new, original, and ornamental Design for an Advertising Display Case, of which the following is a specification, reference being had to the accompanying drawing, forming a part thereof.

The accompanying drawing is a front elevation of an advertising display case embodying the design. The case includes a

number of time and weather indicating devices with panels for advertising matter arranged in proximity thereto, one of said devices being arranged centrally with reference to a plurality of panels which are grouped radially about said device, the other panels being arranged above and below said radially grouped panels.

I claim:

The ornamental design for an advertising display case, as shown and described.

CLARENCE D. OVERSMITH.
